(57) **CLAIM**

The ornamental design for a drawer divider walls as shown and described.

DESCRIPTION

FIG. 1 is a top, front, right perspective view of a first embodiment of drawer divider walls, shown in an illustrative environment;

FIG. 2 is a top, front, right perspective view of the drawer divider walls, shown without the illustrative environment for ease of illustration;

FIG. 3 is a front elevation view of the drawer divider walls of FIG. 2;

FIG. 4 is a back elevation view of the drawer divider walls of FIG. 2;

FIG. 5 is a left elevation view of the drawer divider walls of FIG. 2;

FIG. 6 is a right elevation view of the drawer divider walls of FIG. 2;

FIG. 7 is a top plan view of the drawer divider walls of FIG. 2;

FIG. 8 is a bottom elevation view of the drawer divider walls of FIG. 2;

FIG. 9 is a top, front, right perspective view of a second embodiment of the drawer divider walls;

FIG. 10 is a front elevation view of the drawer divider walls of FIG. 9;

FIG. 11 is a back elevation view of the drawer divider walls of FIG. 9;

FIG. 12 is a left elevation view of the drawer divider walls of FIG. 9;

FIG. 13 is a right elevation view of the drawer divider walls of FIG. 9;

FIG. 14 is a top plan view of the drawer divider walls of FIG. 9; and,

(Continued)

FIG. 15 is a bottom elevation view of the drawer divider walls of FIG. 9.

The broken lines in FIGS. 1-15 are included for the purpose of illustrating portions of the drawer divider walls that form no part of the claimed design. A separation and a bracket in FIGS. 2-15 are included to indicate that the precise length, width, and height of the drawer divider walls are not claimed.

1 Claim, 15 Drawing Sheets
